UNITED STATES PATENT OFFICE.

EDWIN M. BASSLER, OF MILWAUKEE, WISCONSIN.

RADIATOR.

Application filed May 12, 1924. Serial No. 712,671.

This invention relates to radiators.

The object of the invention is to provide a radiator comprising sections made of sheet metal, preferably sheet copper, which will be economically efficient in operation, simple in construction, relatively inexpensive, sufficiently strong to withstand stresses due either to pressure or suction within the same and which will be very light as compared with cast metal radiators, correspondingly reducing shipping costs.

To effect these objects, a radiator embodying my invention and improvements comprises the various features and details of construction hereinafter described and claimed.

In the accompanying drawings, in which my invention is fully illustrated,

Figure 1 is a side view of a radiator section embodying my invention and improvements.

Figure 2 is a plan view thereof, either top or bottom.

Figure 3 is an enlarged sectional view on the line 3—3 of Fig. 1, illustrating the arrangement of said sections in a radiator unit, one thereof being shown complete and the others only in part.

Figure 4 is a view of a radiator unit comprising a plurality of radiator sections, showing said sections as they would appear from the right side of Fig. 1, together with the connecting means therefor; and

Figure 5 is a fragmentary view of a radiator comprising a plurality of connected radiator units similar to that shown in Fig. 4, particularly designed and adapted for heating by forced circulation.

Describing the invention with particular reference to the drawings, A designates a radiator section embodying my invention and improvements as a whole, said radiator sections consisting of plates 1, 1', having flat marginal portions 2 extending entirely around the same and which are respectively provided within the flat marginal portions 2 with corrugations 3, 3' which extend at an angle relative to each other, being preferably inclined at similar opposite angles relative to a horizontal line when said section is in

upright position. Said corrugations may conveniently be formed by stamping, the corrugations in both plates being stamped outwardly with reference to the contemplated plane of contact of the flat marginal edges of said plates, when connected to form the finished section, the relation being such that one set of corrugations will be tangent to the plane of contact of the marginal edges of said plates and the other corrugations will be tangent to the planes of the sides of the finished radiator sections.

The plates 3, 3' are adapted to be rigidly connected to form the radiator section A by soldering, welding or otherwise rigidly connecting the flat marginal flanges 2 of said plates together so as to form a tight joint.

With the construction described, it is obvious that when said plates 3, 3' are connected as described, the corrugations of the plates 3, 3' of the radiator section, which are relatively convex, will rest in contact with each other at their crossing points, thus effectually preventing collapse of the sides of said radiator under suction.

The plates 3, 3', are provided with supply and return openings designated, respectively, 4, 4', preferably formed adjacent to opposite ends of the radiator section, each of said plates comprising an area 5 adjacent to the supply and return openings thereof which is flat and uncorrugated and the outer sides of which are in the planes of the outer sides of said radiator section.

Secured between the flat areas 5 of the plates 3, 3' of the radiator sections A are hollow spacing members 6 which will prevent collapse of the sides of the radiator when subjected to tension applied thereto to draw two or more of said radiator sections into close contact with each other to form a radiator unit having a plurality of sections, as will presently be described.

Said spacing members 6 are preferably circular in shape and are secured in position by flanging the edges of the supply and return openings 4, 4' in the sides of the radiator section, inwardly over the edges of the holes or openings in said spacing members, as shown at 7.

For reasons presently described, said spacing members or rings 6 are made in the form of spiders, comprising central hubs 8 connected to the ring portions thereof by 5 arms 9, the hubs 8 being provided with holes 10 which are preferably concentric with the supply and return openings 4, 4'.

To permit the heating medium—steam or hot water—which enters the supply openings 4 to pass from the hollow interiors of the spacing members or rings 6 into the interiors of the radiator sections A, and from said radiator sections into the spacing members 6 secured in the return openings 4', 15 said spacing members are provided with ports 11 which open through their perimeters, thus connecting the openings within said spacing members with the interiors of said radiator sections.

20 A finished radiator will preferably comprise a plurality of sections A sufficient to provide a desired area of radiating surface.

In the preferable construction shown, any desired number of radiator sections A are 25 adapted to be connected to form a heating unit of desired size by means of end plates 12, 12', applied to opposite ends thereof and which are rigidly connected by tension members 13 which provide means by which the 30 radiator sections may be drawn into close contact with each other, said tension members preferably comprising tension members applied at the supply and return openings 4, 4', thus insuring the formation of tight joints 35 between the flat, uncorrugated areas 5 surrounding the supply and return openings of adjacent radiator sections. If found necessary, packing gaskets may be inserted between the surfaces 5 of adjacent radiator 40 sections, but when said sections are made of soft ductile metal, as copper, no gaskets other than the flat contacting surfaces 5 will be necessary.

In the preferable construction shown, the 45 tension member 13 which extends through the return openings 4' of the radiator sections is tubular and is provided with holes 14, Fig. 3, which communicate with different radiator sections, forming vent openings 50 therefor.

The lower ends of the end plates 12, 12' are preferably finished to form a supporting base for the radiator or, where the radiator is designed for use for heating by forced 55 circulation, both the upper and lower ends of said end plates will be finished so that plates 15 may be secured thereto, Fig. 5, which, with the end plates will provide a casing for the top, bottom and ends of said 60 radiator, to the open sides of which pipe connections may be made, comprising a blower connection to one side thereof.

65 Preferably, also, the lateral marginal edges of the end plates 12, 12' are constructed and arranged so that any desired

number of radiator units may be connected together, thus providing for radiators or heaters having any desired area of radiating surface. As shown, marginal flanges 16 are formed entirely around said end plates 12, 12', thus providing for connecting different radiator units together by bolting the lateral marginal flanges thereof together, while the top and bottom marginal flanges on said end plates are finished to provide seats to 70 which the plates 15 may be secured for enclosing the radiators or, where the radiator is not enclosed, the finished bottom flanges of said end plates will provide a supporting base for the radiators.

The end plates 12, 12', are provided with flanged supply and return connections, 17, 17' to which, respectively, supply and return manifolds 18, 18' are adapted to be connected by means of corresponding flanged 80 connections 19, 19'.

To provide for venting the sections of different radiator units, when the system is not equipped with a vacuum exhaust, each unit is preferably provided with automatic, 90 thermostatic vent valves. Convenient points of application of said vent valves are the supply and return connections 18, 18', both of which are provided with tapped holes, as shown at 20, to receive the threaded end of 95 a vent valve. If vent valves are not used, the openings 20 may be closed by usual screw plugs 21.

While I have herein shown and described my improved radiator sections and radiators 100 as having separate supply and return connections which communicate therewith at opposite ends of said sections, I do not desire to limit myself to the arrangement shown or to any particular arrangement, 105 that shown merely exemplifying any desired or approved arrangement of supply and return, which will vary with different heating media—as steam or hot water—and different return systems—as gravity or vacuum 110 return.

I claim:

1. A radiator section consisting of corrugated sheet metal plates connected at their edges to form a tight joint, the corrugations 115 of different plates crossing each other and comprising corrugations which rest in contact with each other at crossing points, said section being provided with an opening adapted for making a supply connection 120 thereto, and the relation being such that the heating medium will traverse said sections crosswise of the corrugations in its side walls.

2. A radiator section as specified in claim 125 1, which is provided with openings in its side walls adjacent to opposite ends thereof, adapted, respectively, for making supply and return connections thereto.

3. A radiator comprising a plurality of 130

- sections substantially as specified in claim 1, and means for rigidly securing said sections together to form a radiator unit with corrugations of adjacent sections of the radiator in contact and the supply openings of different sections in communication with one another, said connecting means being constructed and arranged to exert pressure on corrugations of the outer sides of the extreme sections of the radiator, thereby preventing the sides of the sections of the radiator from bulging when subjected to internal pressure.
- In witness that I claim the foregoing as my invention, I affix my signature this 6th day of May, A. D. 1924.

EDWIN M. BASSLER.
